UNITED STATES PATENT OFFICE.

WALTER D'ARCY RYAN, OF SCHENECTADY, NEW YORK.

HEADLIGHT.

Application filed September 2, 1924. Serial No. 735,407.

My invention relates to improvements in headlights, and is particularly concerned with improvements in headlights for use upon automobiles and other automotive vehicles.

In Patent No. 1,484,309, granted me February 19, 1924, I have disclosed a novel type of headlight, making use of a shallow reflector, and by means of which the roadway 10 ahead of a vehicle is adequately illuminated, and at the same time the areas adjacent the vehicle, and at the side of the road are also illuminated sufficiently to enable the driver to observe the sign-posts, and 15 other objects at the side of the road.

One of the objects of my present invention is to provide a headlight that will produce substantially the same kind of illumination as that produced by the headlight disclosed in my patent, above referred to, to 20 provide a headlight that will adequately illuminate the areas adjacent the front of the vehicle, and the sides of the road.

Another object in my invention is to provide a headlight of the character described that will even produce illumination to the rear of the headlight so as to illuminate the forward portion of the vehicle by which the headlight is carried, and also to provide 30 illumination ahead of the vehicle when it turns into a cross-road.

A further object in my invention is to produce a headlight of the character described that is simple in construction, economical to manufacture, and rugged.

Other objects in my invention will appear as this description progresses, reference being had to the accompanying drawings, in which:

40 Figure 1 is a side elevation, partially in section, of my improved headlight.

Figure 2 is an end elevation.

Figure 3 is a sectional detail showing a modification of the auxiliary reflector.

45 Referring to the drawings, and in particular to Figures 1 and 2, my improved headlight comprises a housing or casing 2 provided with a door, comprising a supporting ring 3, that may be hinged, or otherwise 50 suitably mounted, upon the casing 2. The supporting ring 3, carries the bowl shaped lens 4, that is held in place by clips 5, secured to the ring 3, and resting against the edge of the lens. A reflector 6 that may be 55 of metal, glass, or any other suitable material, is mounted within the collar 9 car-

ried by the casing 2 and held in place by the clamping ring 10.

A socket 7 is mounted in the bottom of the reflector 6 for receiving the electric lamp 8, the filament of which is located substantially at the focus of the reflector 6.

A conoidal reflector 11 is secured to the central portion of the lens 4 by means of a screw 12, or in any other suitable manner, 65 with the reflecting surface disposed toward the main reflector 6. However, the reflecting surface of the reflector 11 may be paraboloidal, ellipsoidal or of any other curvature, as circumstances may require.

70 By making use of an auxiliary conoidal reflector such as described above, I provide a construction whereby the rays of light issuing from the source 8, substantially directly forwardly, are reflected through the 75 lens in a lateral and rearward direction as indicated by the arrows in Figure 1. Those rays from the source of light that strike the main reflector 6 are reflected in substantially parallel relation, so as to provide an adequate beam of light for illuminating the roadway ahead of the vehicle. The auxiliary reflector 11, not only provides means for reflecting the rays towards the side of the roadway, and to the rear of the headlight, but also acts as a screen to prevent approaching drivers from being blinded by the rays issuing directly from the filament of 80 the lamp.

The top and bottom portions of the conoidal reflector 11 are cut away as indicated at 16, so as to reflect only a portion of the direct rays of light issuing from the lamp 8, and these portions are reflected laterally, or to the sides of the road. This permits 95 direct rays of light from the source to pass through the top and bottom of the auxiliary reflector, to assist in the illumination of the roadway ahead of the vehicle.

100 In the modified form of my invention shown in Figure 3, the lens 4 is provided with a central conoidal depression 17, that may be silvered or otherwise treated to form a reflecting surface. This reflecting surface will then perform the same functions as the 105 reflecting surface of the auxiliary reflector 11, described above.

110 While I have described the details of construction of the preferred embodiments of my invention, it is to be clearly understood that my invention is not limited to these details, but is capable of other adaptations and

modifications within the scope of the appended claims. It is to be further understood that the main reflector may be paraboloidal, hyperboloidal, ellipsoidal, or any 5 other suitable curvature.

Having thus described my invention, what I claim is:

- 10 1. A headlight comprising a reflector, a lens for said reflector, a source of light in said reflector, and an auxiliary reflector carried by the central portion of said lens, for reflecting the light from said source through marginal portions of said lens, the top and bottom portions of said auxiliary reflector 15 being cut away to permit the passage for-

wardly of direct rays of light from said source.

2. A headlight comprising a reflector, a lens for said reflector, a source of light in said reflector, and an auxiliary reflector carried by the central portion of said lens for reflecting light from said source through marginal portions of said lens, a portion of said auxiliary reflector being cut away to permit the passage forwardly of direct rays 20 25 of light from said source.

In witness whereof, I hereunto subscribe my name this 5th day of August, 1924.

WALTER D'ARCY RYAN.
